United States Patent Office.

JOHN BURT, OF DETROIT, MICHIGAN.

Letters Patent No. 65,054, dated May 28, 1867.

IMPROVEMENT IN CANAL LOCKS.

The Schedule referred to in these Letters Patent and making part of the same.

TO WHOM IT MAY CONCERN:

Be it known that I, JOHN BURT, of Detroit, in the county of Wayne, and State of Michigan, have invented certain new and useful Improvements in Canal Locks; and I hereby declare the following to be a full, clear, and exact description of the same, reference being had to the accompanying drawings.

My invention has reference to the method of and means employed for raising or lowering the level of water in canal locks or chambers for effecting the transfer of boats from one level to another of the canal. The ordinary method of accomplishing this is by means of sluices, sometimes formed in the sides of the lock, but oftener in the water-gates which close the ends of the lock-chamber, by the opening and closing of which sluices water is introduced into the chamber at one end from the upper level of the canal, or drawn off and discharged from the chamber at the other end into the lower level. This arrangement, however, is defective in important respects. For instance, suppose that the upper sluices are opened in order to fill the chamber, the water from the upper level being under pressure of course enters the lock with considerable force, and is driven against the lower gates; meeting resistance there, it flows back towards the other end of the chamber to again meet the strong current entering through the open sluices, and so the water in the chamber surges backward and forward, the violence of the motion being greater or less in proportion to the size of the sluices and the volume of water under pressure. This motion will of course affect the boat or vessel in the lock at the time, and in order to prevent it from being driven by the flux and reflux of the water against the gates or the sides of the chamber, it must be tied up to piles or posts placed on top of the lock. The same defects are apparent when the water is drawn off, the water within the lock-chamber being agitated to such an extent that the boat, as before, must be tied up or secured to the sides of the lock. Under this arrangement the only means of checking the surging of the water is to decrease the size of the sluices, but by doing this the operation of raising or lowering the boat will necessarily consume more time and give rise to considerable delay.

Now, the principal object of my invention is to so introduce the water into the lock as to prevent it from having any undue motion, but at the same time to allow of any desired quantity being admitted at once; or, in other words, to fill or empty the lock with greater expedition than is done by the old plan, and at the same time to keep the water sufficiently free from motion to obviate the necessity of tying up the boat or vessels in the lock-chamber. To this end my invention consists in introducing and discharging the water into and from the lock through the bottom or floor of the chamber in such manner that the water shall enter or leave the chamber simultaneously throughout the whole area of the floor of the lock. To do this, I employ, preferably, a series of tubes opening at one end into the upper level of the canal, and thence extending downward into the floor or bottom of the lock, over which they pass, and then open into the lower level of the canal. These tubes or conduits are provided at each end with valves for regulating the flow of the water, which valves are connected or coupled together, so that all the tubes may be opened or closed at either end simultaneously, and the portions of the pipes which pass over the bottom of the lock-chamber have formed in them at intervals holes or apertures through which the water is discharged into or drawn off from the lock. By this method the bottom of the lock-chamber in effect constitutes a diaphragm through which the water passes in a diffused state quietly and without surging. No matter how great the size of the tubes, the distribution over the bottom of the lock of the apertures through which the water passes will check and effectually prevent any violent movement of the water.

My invention further consists in an improved construction and arrangement of the valves for opening and closing the mouths of the tubes, and also in so constructing the water-gates as to endue them with a certain springiness or elasticity and strength, in order that when pressed against by the superior column of water in the upper level of the canal, or in the lock itself, the gates may be pressed firmly and tightly into the ways in which they slide, and thus prevent the escape of the water.

To enable others to fully understand my improvements, I will now proceed to describe the manner in which the same are or may be carried into effect by reference to the accompanying drawings.

Figure 1 represents the general features of my system.

U is the upper level of the canal, and L the lower level. The upper water-gate A of the lock is a sliding gate of ordinary construction. The tubes or conduits *a* which lead the water from the upper level into the lock-chamber open into the upper level, and extend side by side under the gate A down to the bottom *b* of the

lock. There they turn or are bent so as to pass over and along the bottom *b* until they leave the lock and extend out into the lower level, as shown at *a'*. The portions of tubes *a* which extend along the floor of the lock have apertures or perforations formed in them at intervals, as shown at *c c*, Figure 5, for the purposes above mentioned. The upper mouths of the tubes are fitted with ordinary valves, shown at *B*, Figure 3, coupled or linked together by means of a rod, *C*, to which the cranks for moving the valves are secured. As the lower valves of the conduits *a* are subjected at times to heavy pressure, especially if the "lift" of the lock, or the difference between the levels be considerable, I construct them as shown in Figure 2. The valve *d* is tubular, and open at its outer end. It has a conical form, so as to fit tightly in its seat *d'*, which likewise has a tubular shape, and is inserted in the end of the conduit *a*. Two apertures, *e*, diametrically opposite each other, are formed in the valve-seat, and like apertures, *e'*, are made in the valve, so that when, by the rotation, the openings *e e'* are brought together the water in the conduit will flow fully through the apertures out from the open end of the valve. The object of making the two apertures *e e'* in opposite sides of the valve-seat is to equilibrate the pressure of the water upon the valve when the latter is closed, so as to avoid all friction or hindrance in working the valves. This friction, which is comparatively unimportant in operating a single valve, becomes very noticeable when a series of valves is coupled together, as shown in Figure 4, and the arrangement devised by me is intended to obviate this difficulty by making the pressure of the water the same on both sides of the valve. Instead of arranging the tubes as shown in the drawing, the upper conduits need only extend down as far as the bottom of the lock, which may be fitted with a false bottom, *k*, perforated at *c*, so as to form a diaphragm, as shown in Figure 6, which, in many instances, can be used with as good effect as the perforated tubes. In this case the water should be drawn off by tubes arranged in the lower end of the lock, to which the valves shown in fig. 2 can be fitted, as explained. In connection with the lock I use a gate, constructed and arranged substantially as shown at *D* in fig. 1, where it is applied to the lower end of the lock. This gate by virtue of its construction is endowed with great strength and a certain degree of elasticity which enables it, when pressed against by the body of water within the lock, to expand or widen, so as to keep its sides firmly against the ways in which it slides, and thus prevent the escape of any water. In order to impart to the gate this elastic property, I construct it of steel, or steel plates riveted together, and give it a curved shape laterally, the curve being towards the interior of the lock, or in the direction from which the pressure comes. The gate is arranged to slide vertically in upright quoins or guides *E*, and has attached to it chains or wire cables passing over the top of the frame *E*, from which are suspended compensating weights *n*, which so nearly equilibrate the weight of the gate that when there is no pressure upon the latter, the operator, to raise the gate, has only the friction to overcome. This gate may be used, of course, at either or both ends of the lock, though I have shown it only at that end where the gate is subjected to the greatest pressure. By constructing the gate of metal, as described, and giving it a curved form, I am enabled to make it of great strength, especially as it is solid, and has none of the sluices or wickets by which the strength of ordinary gates is impaired. In locks where it is desirable to obtain all the room possible, the gates may be turned so that the curve shall be outwards from the chamber, and in this case they will be held tightly against the guides or quoins by pressure of the water against their concave sides.

The lock is operated as follows: Suppose the water in the lock is to be raised from the lower to the higher level of the canal. The gate *D* is first shut, and then the lower valves *d* being closed, the valves *B* are opened. The water enters the conduits *a*, passes down through them to the bottom of the lock, and then enters the chamber through the aperture *c*. The great volume of water which is drawn in through the valves *B* by this means is caused to enter the chamber in a diffused state, being at once spread over the whole extent of the chamber, and thus prevented from surging, or moving the boat or vessel contained in the lock. As soon as the water in the lock has attained the level of the upper "pound" or portion of the canal, the gate *A* is opened and the canal-boat is towed out. When the lock is thus filled, the superior column of water then presses against the lower gate *D* with a force proportionate to the height of the "lift," or the difference between the two levels, and causes the gate to expand laterally, its sides being forced tightly and firmly against the ways *E* in which it slides, and, by this means, the greater the pressure of the water against the gate the tighter it is pressed in its seat, thus effectually preventing the water from escaping. When the water in the lock is to be brought down to the lower level, the valves *B* are closed and the valves *d* opened. The water is now drawn off simultaneously from all points of the floor or bottom of the chamber, and consequently leaves the lock quietly and without disturbance. As soon as the water in the lock has reached the lower level, the gate *D* may be raised with perfect ease, for the water now presses against both of its sides with equal force, leaving nothing but the friction to overcome, as above explained.

Having described my invention, and the manner in which the same is or may be carried into effect, what I claim, and desire to secure by Letters Patent, is—

1. Discharging the water into and from the lock-chamber of a canal in a diffused or divided state by means of a diaphragm or apertures formed in the bottom of the said chamber, substantially as shown and described.
2. Discharging the water into and from a canal-lock, the same consisting of tubes or conduits communicating with the higher and lower levels of the canal, and extending along the bottom of the lock-chamber, and perforated so as to allow the water to enter or be drawn off from the said chamber at several points simultaneously and in a diffused state, substantially as shown and set forth.
3. The combination with the said tubes or conduits of the valves for regulating the flow of the water, the said valves at each end of the tubes being coupled or united together so as to be operated simultaneously, substantially as shown and set forth.
4. The combination, with a tubular valve-seat in which apertures are formed diametrically opposite each other, of a tubular valve provided with corresponding apertures, the said valve and valve-seat being arranged for operation, relatively to the water-tube or conduit, substantially as shown and specified.

5. The water-gate herein described, the same being made of steel or other suitable elastic material, and having a curved shape, as specified, so that when under pressure the sides of the said gate shall be held firmly and tightly against the quoins or guides in which it slides, as shown and set forth.

6. The combination, with the elastic water-gate, sliding vertically in quoins or guides, of the compensating weight for equilibrating the said gate, substantially as shown and described.

In testimony whereof I have signed my name to this specification before two subscribing witnesses.

JOHN BURT.
